US0D1025203S

(12) **United States Design Patent** (10) **Patent No.:** **US D1,025,203 S**
(45) **Date of Patent:** **** Apr. 30, 2024**

(54) **CUTTING MACHINE**

(71) Applicant: **Beaver technology (Shenzhen) Co., Ltd.**, Shenzhen (CN)

(72) Inventors: **Muyang Wen**, Shenzhen (CN); **Han Chen**, Shenzhen (CN)

(**) Term: **15 Years**

(21) Appl. No.: **29/901,965**

(22) Filed: **Sep. 7, 2023**

(51) **LOC (14) Cl.** **18-04**

(52) **U.S. Cl.**

USPC **D18/34.8**

(58) **Field of Classification Search**

(57) **CLAIM**

The ornamental design for cutting machine, as shown and described.

DESCRIPTION

FIG. 1 is a perspective view of cutting machine showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is an enlarged view of portion 9 shown in FIG. 7;

FIG. 10 is an enlarged view of portion 10hown in FIG. 7;

FIG. 11 is an enlarged view of portion 11hown in FIG. 7; and,

FIG. 12 is an enlarged view of portion 12hown in FIG. 7. The dot-dash broken lines represent boundaries of the enlarged portions and form no part of the claimed design. The evenly spaced broken lines depict portions of the cutting machine that form no part of the claimed design.

1 Claim, 12 Drawing Sheets
